UNITED STATES PATENT OFFICE.

NEWMAN T. BROWN, OF SEATTLE, WASHINGTON.

MOTOR-CAR SIGNAL.

1,347,246.

Specification of Letters Patent.

Patented July 20, 1920.

Application filed February 20, 1918. Serial No. 218,277.

To all whom it may concern:

Be it known that I, NEWMAN T. BROWN, a citizen of the United States of America, residing at Seattle, county of King, State 5 of Washington, have invented certain new and useful Improvements in Motor-Car Signals, of which the following is a specification.

This invention relates to signals for 10 motor cars and other vehicles; and it proposes a device or mechanism of the general class or type specified embodying certain improvements, hereinafter fully described, by, or as a result of, which the signal proper 15 may be readily swung into and out of operative position and, when in the former position, is illuminated by a suitable lamp, the light rays of which are visible from front, back and side of the car. The invention is 20 preferably of a duplex character, in so far as it contemplates the provision of one of the above described signals at each side of the car, thereby enabling the direction in which the car is about to turn, or its stop- 25 page, to be readily determined, according as one signal or the other is operated individually, or both are operated simultaneously.

According to the invention, there is 30 mounted in a casing arranged at each side of the car and partially closed by a pivoted side plate, a signal arm which is slidably carried by said plate so as to move outwardly and inwardly therewith during the 35 movements of the arm. The plate itself is connected with an actuating segment, which is arranged within the casing and connected in turn with an operating device, there being, of course, one of these operating devices 40 for each signal arm. The operating devices themselves are so constructed and arranged that either may be actuated independently of the other, according to the direction of the contemplated turn, or both may be actuated simultaneously when the car is about to be stopped. The particular structural details of the above described parts or devices, 45 as well as their relative position and arrangement, constitute the important features of my invention and will be explained in due course and set forth in the appended

claims. It is to be understood, however, that the invention is not limited to the precise details shown and described, excepting as specified in the said claims, but, on the contrary, that modifications and changes may be made within the scope of said claims, and that parts of the invention may be used either by themselves or with parts of a different character from those disclosed. 60

In the accompanying drawing:

Figure 1 is a fragmental side elevation of a motor car, with parts broken away for the sake of clearness, showing the invention in use. 65

Fig. 2 is an enlarged side elevation of the signal in its normal or inoperative position.

Fig. 3 is a horizontal section on line 3—3, Fig. 2.

Fig. 4 is a view similar to Fig. 3, but 70 showing the signal in its extended or operative position.

Fig. 5 is a longitudinal, vertical section on line 5—5, Fig. 3.

Fig. 6 is an enlarged detail view, showing 75 the carrier for the signal arm.

Figs. 7 and 8 are, respectively, a side elevation and a plan view of the device for controlling the movements of the carriers.

Referring more particularly to said drawing, 1 indicates, generally, an elongated casing which is secured horizontally to the side of the tonneau of the car by suitable brackets 2, which latter may well extend beneath the upper edge of the upholstery, as shown. 80 It is intended, of course, that there shall be one of these signal-containing casings at each side of the tonneau, but for illustrative purposes, it is deemed sufficient to represent one only; and in any case, a description of 85 one will apply to both. The casing 1 includes an elongated, vertically-disposed back plate 3 formed with upper and lower out-turned marginal flanges 4 which gradually increase in width from their rear ends 90 to a point adjacent their front ends, and then decrease from such point to their last-named ends.

The two horizontal flanges 4 are provided, adjacent their inner edges and substantially 100 at the point of greatest width just referred to, with bearings in which are mounted the

ends of a vertical pivot bolt 6 which is set comparatively close to the car side. To this bolt are connected a pair of spaced ears 6', formed upon the free edges of the front 5 member 6³ of an angular, vertical plate 6², the rear member 6⁴ of which has integrally connected to it a rearwardly-extending wing 6⁵, which, when the said plate is in normal position, is located below the free outer edges 10 of the flanges 4. The bolt 6 may be rigidly fastened to said flanges 4, and the ears 6' loosely mounted on it, or, if preferred, it may be loose in said flanges and rigidly attached to said ears. The plate extension 6⁵ 15 has fastened to it one end of an outwardly-swinging arm 5, which forms a substantial closure for the open side of the casing, said arm 5 having its upper and lower marginal edges provided with angular flanges 10, 20 which serve to materially strengthen it and also as guides for a sliding signal arm 11 which is carried in this manner by the arm 5 and has its outer end 12 shaped as an arrow head.

25 The portion of the open outer side of the casing in advance of the arm 5 is closed by front and rear plates 7 and 8, the former of which is fixed in any suitable manner to said casing and has its rear edge cut centrally 30 away to form a pocket 7' for the reception of a central, projecting tongue 8' provided on the front edge of the plate 8, the two plates 7 and 8 being connected at this point by a vertical hinge bolt or pintle 9, so as to 35 enable the tongue end of the plate 8, to move inwardly of the casing, while its rear end swings outwardly thereof and is provided with a cross-strap 14 which extends across and is connected to the adjacent end of the 40 signal arm. The arrangement is such, therefore, that when the plates 7 and 8 are in their normal positions, the entire front of the casing will be closed to exclude snow, hail, rain and the like, the front plate 7 remaining closed under all conditions so as to 45 constantly preclude the entry of dust, dirt, gravel, etc., into the front of the casing while the car is in motion. When the signal is operated, however, in the manner subse- 50 quently explained, the plate 6² will swing bodily outward upon its pivot 6, and will rock the plate 8 with it in the same direction about its pivot 9, the rear end of the latter plate moving outward of the casing 55 and the short rear end moving inward thereof, as represented in Fig. 4.

The movements of the angular plate 6² may be effected with the aid of any means or device desired; but it is preferred to make 60 use of a wire, cable or other flexible element 16, which passes around and is secured at one end to a grooved sector 15, the other end of the cable leading through a suitable guide tube 17 passing between the side of the car 65 and the upholstery and extending the entire

distance from the signal arm to the subsequently described control. As two signals, one at each side of the car, are preferably employed to indicate the direction in which the car is about to turn, it is essential, of course, 70 to provide means whereby either signal may be operated independently of the other, or both may be operated simultaneously in case it is desired to indicate stopping of the car. In the embodiment illustrated, which may be 75 regarded for all practical purposes as preferred, there is one of the sectors 15 for each cable, as will be understood, each sector being integrally or otherwise rigidly connected to the lower edge of the front member 6³ 80 and adjacent ear 6' of the corresponding angular plate 6². The front end of each cable or other flexible operating element is fastened to a grooved pulley 18, which is rotatably mounted in an appropriate manner 85 upon the steering post of the car, or upon some other suitable support, and has secured to it an operating lever 19, the result being that either lever can be actuated independently of the other to turn its respective pulley and, in consequence, wind up the 90 respective cable to shift the corresponding signal outward.

In order to enable both pulleys 18 to rotate at the same time and, hence, to swing 95 both signal arms outward simultaneously, there is preferably utilized a third lever 20, which is arranged between the two levers 19, (which are disposed in spaced, parallel relation, as depicted in Fig. 8), and is provided adjacent its inner end with a bridge piece 21, which spans the two pulleys and is so arranged as to turn them both at the same 100 time when the lever 20 is depressed.

To return the various parts to their 105 respective initial positions, any desired means or devices may be employed, the returning devices preferably consisting, however, of a spring 22 for each sector 15, which is anchored at its rear end to the back plate 3 110 of the casing and is attached at its front end to a brass strip 23, which runs along the bottom flange or wall of the casing and passes beneath and is secured to the sector.

Finally, each casing is preferably 115 equipped with an electric lamp 24, having associated with it a reflector 25 and being disposed within a suitable electric circuit 26, which is closed by a switch 27 of some kind. According to the preferred form of the invention, the lamp 24 and its reflector 25 are disposed in line with a cut-away portion 28 of the wing 6⁴ of the angle plate 6² and, also, with an opening provided in the plate 7 at the point 7', one due to the tongue 8' of the 125 plate 8 moving inwardly into the casing as the main part thereof swings outward, and the other produced by cutting away part of the casing, as indicated at 29. In this way, it is possible for the light rays to shine along 130

both sides of the signal arm; thus displaying the position of the latter to persons standing both in front and at the back of the car. In addition to the above, the wing 6³ of the 5 plate 6², which assumes a position transverse to the casing when the signal arm is extended, is provided with a pane of transparent ruby glass 30, through which the light rays pass when said wing occupies its 10 normal position, thereby enabling the light to shine through the far end of the casing.

I claim as my invention:—

1. A turning and stopping signal, comprising a casing having a movable closure; a signal in said casing mounted on said closure; means for opening said closure; and means for automatically projecting said signal when said closure is opened longitudinally of and beyond the outer end of 20 the closure.

2. A turning and stopping signal, comprising a casing having an outwardly-swinging closure; a signal mounted slidably on said closure and normally housed in said 25 casing; means for swinging said closure outwardly; and means for automatically sliding said signal longitudinally of and beyond said closure when the latter is so swung.

3. A turning and stopping signal, comprising a casing having an outwardly-swinging closure; a signal mounted slidably on said closure and normally housed in said casing; means for swinging said closure outwardly; and means connected at one end 35 with said signal and at its other end with a point spaced laterally from the pivot of said closure, thereby to slide said signal beyond said closure when the latter is swung outwardly.

4. A turning signal, comprising a casing having an outwardly-swinging closure formed with parallel guide and reënforcing flanges along its side edges; a signal arm received normally in said casing and supported slidably by said flanges; means for swinging said closure outwardly; and means for automatically sliding said signal arm beyond an end and longitudinally of said closure when the latter is so swung.

5. A turning signal, comprising an elongated back plate having outwardly extended flanges along its side edges; an outwardly-swinging, pivoted arm between the outer edges of said flanges and extending substantially throughout the length thereof, the pivot of said arm being spaced inwardly from one end of said flanges; a signal arm mounted slidably on the inner side of said pivoted arm; a plate pivoted between said flanges with its free end adjacent the pivoted end of said pivoted arm; means connected with said plate and attached to said signal arm for projecting the latter when said pivoted arm is swung outwardly; and means 65 for so swinging said pivoted arm.

6. In a turning signal, a casing open in part along one side, a pivoted arm operating in the opening of said casing side, a plate pivoted independent of the arm and connected to the latter and having one end closing one end of said casing opening, and means to operate the arm. 70

7. A turning signal, comprising a support; an arm pivoted to said support to swing outwardly therefrom; a lamp fixed to 75 the support behind the pivot of said arm for illuminating both sides of said arm when the latter is extended; and means for swinging said arm outwardly to extended position.

8. A turning signal, comprising an arm to 80 be projected beyond the side of the vehicle; and a fixed light mounted independently of the arm and located at the inner end thereof for illuminating both sides of said arm when the latter is extended. 85

9. In a motor car signal, the combination of a casing; a pivotally mounted carrier within said casing; a signal arm associated with said carrier to move therewith outward and inward of the casing; said carrier including a member having a pane of ruby glass set thereinto; means for actuating said carrier; and illuminating means, including a lamp arranged to project its rays through said ruby glass to be visible through the end 95 of the casing. 90

10. In a motor car signal, the combination of a casing; a pivotally mounted carrier within said casing; a signal arm associated with said carrier to move therewith outward 100 and inward of the casing; and illuminating means, including a lamp arranged to project its rays along both sides of said signal arm when the latter is in projected position.

11. In a turning signal, a casing having 105 an opening in one side, a substantially Z-shaped member pivoted at one end in the casing, a signal arm operating in said opening and borne by the other end of said member, and means to operate said member. 110

12. In a turning signal, a casing having an opening in one side, a substantially Z-shaped member pivoted at one end in the casing, a signal arm operating in said opening and borne by the other end of said member, and a plate pivoted to one side of the pivot of said member and connected at one end to the last named end of the member and having its other end providing a closure for the adjacent end of the opening. 115

13. In a turning signal, a casing having an opening in one side, a signal arm pivoted to the casing for closing one end of the opening thereof when the arm is in inoperative position, a plate pivoted independent of the arm for closing the opposite end of the opening, means to operate the arm into and out of display position, and means to actuate the plate by the arm movements. 125

14. In a turning signal, a casing, a pivoted 130

member in the casing, a lamp to one side of the pivot, a signal arm carried by the member and arranged to extend radially of the lamp when in display position, and a window formed in the member to allow the lamp to illuminate the side of the arm adjacent to the member pivot.

In testimony whereof I have hereunto set my hand in presence of two subscribing witnesses.
